CLAIM

The ornamental design for a syringe, as shown and described.

DESCRIPTION

FIG. 1 is a top, left, front isometric perspective view of a syringe in accordance with the present design;

FIG. 2 is a right side elevation view of the syringe;

FIG. 3 is a left side elevation view of the syringe;

FIG. 4 is a top plan view of the syringe;

FIG. 5 is an enlarged front elevation view of the syringe; and,

FIG. 6 is an enlarged rear elevation view of the syringe.

The broken lines illustrate portions of the syringe which form no part of the claimed design.
